UNITED STATES PATENT OFFICE.

ERVIN HOMRIGHOUSE, OF SHELBYVILLE, ILLINOIS.

JEWELING-MACHINE.

SPECIFICATION forming part of Letters Patent No. 293,249, dated February 12, 1884.

Application filed May 21, 1883. (Model.)

To all whom it may concern:

Be it known that I, ERVIN HOMRIGHOUSE, a citizen of the United States, residing at Shelbyville, in the county of Shelby and State of Illinois, have invented a new and useful Machine for Jeweling Watches, of which the following is a full, clear, and exact description, reference being had to the accompanying drawings and letters of reference marked thereon, to which—

Figure 1 is a perspective view of my improved machine for jewelng watches. Fig. 2 is a front elevation of the same, partly in section; and Figs. 3, 4, and 5 are views of the jewelng-tools used with this machine.

Similar letters indicate like parts in all the figures.

My invention relates to improvements in machines for jewelng watches; and it consists in the peculiar construction and arrangement of the parts, as hereinafter more fully set forth, and pointed out in the claims.

In the accompanying drawings, J represents a circular face-plate, provided with a central opening, r, and opposite lugs, e e, having central holes for the passage of the screws of the clamps C C, by means of which the watch plate or bridge R is secured to the face-plate J by means of the thumb-nuts h.

P represents a frame, secured at its lower end to the circumference of the face-plate J, and provided with the parallel lugs H I, having central holes, the former of which is threaded to receive the hollow screw-nut g.

B represents a hollow spindle, which passes through the central hole in the lug I and through the hollow screw-nut Q, and is screw-threaded at its lower end, as shown in Fig. 2, to be screwed to a centering or other tool, hereinafter described.

i represents a handle secured to the hollow spindle B near its upper end.

1 represents a hollow screw-nut secured to the handle i.

a represents a centering-tool, provided with tapering spring-jaws, secured at their upper ends to the head of the centering-tool a. The head of the centering-tool a is provided with a central threaded hole, and is screwed upon the lower end of the hollow spindle B.

K represents a spreader or rod threaded at

its upper end, and passing through the hollow screw-nut 1, thence through the hollow spindle B, the centering-tool a, thence passes through the hole in the work and the hole r 55 in the face-plate J. The spreader K, by its operation, serves to spread laterally the jaws of the centering-tool a, to fill up the hole in the watch plate or bridge R. The spreader K is provided near its middle with a flattened 60 surface, s. (See Fig. 2.) E is a pin passing through the hollow spindle B and over the flattened surface on the spreader K, and thereby prevents the latter from turning, excepting with the hollow spindle B.

O represents a friction-spring, to press against the hollow spindle B and hold it in position.

b (see Fig. 3) represents a bezel-opener, the head of which is provided with a threaded central hole, adapting it to be screwed on the end of the hollow spindle B after the centering has been completed and it is desired to open the bezel for the reception of the jewel.

Fig. 4 represents a closer and burnisher, intended to turn down the bezel on the jewel after it is in place; and Fig. 5 represents a bed and bezel-cutter designed expressly for new work.

All these attachments are to be made of steel, 80 are adjustable to any size required, and are interchangeable on the end of the hollow spindle B.

The pressure of the spring O on the hollow spindle B is sufficiently great to hold it in any 85 desired position to which it may be adjusted, and the function of the hollow screw-nut Q is to adjust the tool secured to the lower end of the hollow spindle B downwardly by screwing the nut Q down until its lower end comes in contact with the head of the tool and forces the latter and the hollow spindle down against the tension of the spring O. The tool is adjusted 90 upwardly by screwing up the hollow screw-nut Q, and then raising up the hollow spindle B and its attached tool bodily by the handle i, the spring O holding the hollow spindle and its attached tool in its raised position.

The operation of the machine is as follows: The watch plate or bridge is placed upon the 100 face-plate of the machine, the centering rod or spreader introduced into the old jewel-open-

ing, and the centering-tool adjusted to the size of the hole by the spreader. The clamp-plates are then secured upon the work. The centering-tool is then removed and replaced by the 5 bezel opener and burnisher, which bezel-opener is adjusted by the hollow screw Q, and the handle *i* rotated until the opening in the work is enlarged sufficiently to receive the jewel. The bezel-opener is then removed from the 10 hollow spindle B and replaced by the bezel closer and burnisher, which closes in and burnishes down the bezel on the jewel, which completes the operation.

What I claim as my invention is—

15 1. In a machine for jeweling watches, the combination, with a hollow spindle journaled in a suitable frame over a face-plate provided with a central hole, of an expansible tool secured to the lower end of the hollow spindle, a spreader passing through said spindle, and means for forcing the spreader downward to spread the jaws of the tool, substantially as shown and described.

20 2. In a machine for jeweling watches, the combination, with the face-plate J, provided with a central hole, *r*, and frame P, secured to said face-plate, of the hollow spindle B, pro-

vided with handle *i*, hollow nut 1, threaded spreader K, and an expansible tool, substantially as shown and described. 30

3. In a machine for jeweling watches, the combination, with the face-plate J, provided with a central hole, *r*, and frame P, secured to said face-plate, of the hollow spindle B, provided with handle *i*, hollow nut Q, and threaded 35 bracket H, substantially as described, and for the purpose set forth.

4. In a machine for jeweling watches, the combination, with the frame P, provided with the bracket H and bracket I, of the hollow 40 spindle B, the hollow screw-nut Q, and the spring O, substantially as shown and described.

5. In a machine for jeweling watches, the combination, with the face-plate J, having a central hole, *r*, and frame P, secured to the 45 face-plate, of the clamps C, hollow spindle B, handle *i*, hollow nut 1, threaded spreader K, hollow nut Q, and threaded bracket H, substantially as shown and described.

E. HOMRIGHOUS.
